CARRYING CASE

Sidney Platt, Highland Park, Ill., assignor to Platt Luggage,
Inc., Chicago, Ill., a corporation of Illinois

Filed Sept. 19, 1961, Ser. No. 66,760

Term of patent 14 years

(Cl. D87—5)

Fig. 1

Fig. 2

Fig. 3

Fig. 4

FIGURE 1 is a perspective view of a carrying case showing my new design;

FIGURE 2 is a bottom view thereof;

FIGURE 3 is a perspective view of the carrying case in open position;

FIGURE 4 is a perspective end view.

The characteristic features of my design reside in the portions shown in full lines and comprise a carrying case having two hingedly connected sections, each generally triangular in cross section and joined to provide a parting line which extends diagonally upwardly from a position adjacent one side of the supporting base portion of the carrying case to a position at the top of the carrying case adjacent the opposite side thereof, in combination with the truncated side edge of the base portion so as to render the case asymmetrical in cross section.

This application is a continuation-in-part of my earlier co-pending application Serial No. D. 63,330, filed December 27, 1960, now abandoned.

I claim:

The ornamental design for a carrying case, substantially as shown and described.
